UNITED STATES PATENT OFFICE.

RUDOLF C. G. STAATS-OELS, OF BROOKLYN, NEW YORK.

ROTARY ENGINE.

Application filed September 30, 1925. Serial No. 59,483.

This invention relates to improvements in internal combustion engines, and has particular reference to an engine of the rotary type.

5 An object of the invention is to provide an improved engine wherein a rotary impeller and a rotary reaction vane are utilized to form the combustion chamber and wherein the movement of the vane after each explosion in the chamber is controlled by the injection of compressed fluid into the engine cylinder.

10 The above and other objects will appear more clearly from the following description 15 when taken in connection with the accompanying drawings which illustrate a preferred embodiment of the inventive idea.

In the drawings:

Fig. 1 is a longitudinal section through 20 the engine constructed in accordance with the invention.

Fig. 2 is a transverse section therethrough.

Fig. 3 is a fragmentary sectional view 25 illustrating a portion of the control mechanism for the impeller and reaction vane.

Fig. 4 is a view similar to Fig. 3 showing the parts in a different position.

Figs. 5 to 10 inclusive are diagrammatic views illustrating the cycle of operation 30 during one revolution of the engine shaft.

Fig. 11 is a top plan view of packing strips employed in connection with the invention.

Fig. 12 is a side view of the packing strips.

35 Fig. 13 is a sectional view of the valve utilized to control the admission of the combustible mixture into the engine cylinder.

Fig. 14 is a sectional view of the detail 40 showing the manner of securing the reaction vane about the engine shaft.

Referring more particularly to the accompanying drawings, the numeral 15 indicates the engine cylinder having the heads 16 and 17 at each end thereof.

45 The cylinder has extending therethrough, the engine shaft 18, mounted in suitable bearings in the heads 16 and 17.

The rotary impeller 19 is secured to the shaft 18 to rotate therewith, while the rotary reaction vane 20 is mounted upon the shaft 18 for relative movement thereto. For this purpose the vane is provided at each end thereof with split hub portions 21 (see Fig. 14) secured together about the shaft 18 by 50 means of screws 22 or other suitable fasteners. These hub portions are interposed

between the ends of the hub portion of the impeller 19 and the cylinder heads 16 and 17.

The impeller and vane combine to form a combustion chamber 23 therebetween, as 60 shown in Fig. 2, into which a combustible mixture is fed and ignited by suitable spark plug 24 mounted in the cylinder head 17. The combustible mixture is supplied through a suitable compressor (not shown) connected 65 to the pipe 25 and also to a valve 26 of any desired construction, said valve being controlled by a cam 27 mounted upon one end of the shaft 18.

The valve 26 is connected to the cylinder 70 head 16 by a pipe 28 joined to a bushing 29 in which is disposed a spring pressed ball valve 30 for normally closing the opening into the combustion chamber. When the cam 27 is operated to open the valve 26, 75 pressure of the combustible mixture forces the valve 30 open, and thereby permits ingress of the mixture into the chamber 23. After the explosion takes place, the force thereof will again close the valve 30 and 80 prevent any further mixture entering said chamber.

The outer peripheries of the impeller 19 and vane 20 have countersunk therein sets of packing strips 31 and 32, springs 33 being 85 provided to exert outward pressure upon the packing to maintain the same in close contact with the inner walls of the cylinder 15. The intermediate strip 32 of each set is split with the inner ends arranged in overlapping relation and having interposed therebetween a spring 34, which exerts an outward pressure upon the strips to maintain the ends thereof in contact with the cylinder heads. 90

95 It is proposed, in connection with the present invention, to utilize compressed air in the operation of the engine to accomplish the rotation of the reaction vane, following the ignition of the combustible mixture in 100 the chamber 23 and consequent rotation of the impeller 19, the rotation of said vane being utilized for the purpose of assisting in the exhaust of the burnt gases from the cylinder and also to permit the impeller 19 105 to continue its rotation after completing the first revolution. In order to rotate said vane 110 the cylinder head 16 is provided at a point substantially diametrically opposite the combustible mixture inlet, with an air inlet to which is connected a pipe 35, which is in turn connected to an air valve 36

through which compressed air passes from a suitable source of supply (not shown). The valve 36 is similar in construction to the valve 26 and is also controlled by the cam 27 so that air will be injected into the cylinder 15 behind the reaction vane 20 before the impeller has passed the air inlet as it is being revolved by the ignition of a combustible mixture behind the same.

10 In connection with the control of the reaction vane there is provided a mechanism which is operated to lock the reaction vane in the position shown in Fig. 2, and at the time that the explosion in the chamber 23 takes place, and which mechanism is also released at a definite point in the operation to permit of the rotation of said vane 20. This mechanism consists of a plurality of spring pressed locking pins 37 supported in brackets 38 secured to the top of the cylinder 15 and each operated by a rocker arm 39, pivoted to the associated bracket 38.

The shaft 40 extends through the ends of the various rocker arms 39 and at one end thereof has connected thereto a rod 41, the opposite end of which is pivoted to another rocker arm 42, pivotally mounted upon the cylinder head 17. One end of this rocker arm has a bearing on a cam 43 mounted upon the shaft 18, so that the operation of the various locking pins 37 is controlled by the rotation of the shaft.

The reaction vane 20 is provided in its outer end with a plurality of recesses 44 in the face thereof, adjacent the impeller 19, and communicating with each of said recesses is a radially extending opening 45 of a greater depth than the recess and adapted to receive one of the locking pins 37 when the vane is in the position shown in Fig. 4, at which time the cycle of operation starts.

At a certain stage of the operation, following the release of the vane 20, the speed of rotation of said vane will be such that the same will approach the impeller 19 and be interlocked therewith. For this purpose the vane carries in each of its recesses 44, a spring pressed latch 46 which will engage over a pin 47 disposed in a recess 48 in the impeller. This interlocking engagement continues until the vane and impeller approach the position shown in Fig. 4. At this time the cam 43 operates the rocker arm 39 to permit of inward movement of the pins 37 into the recesses 44. The inner ends of the pins then engage the various latches 46 as shown in Fig. 3 to release the same from engagement with the associated pins 47. This will permit the impeller to become detached from the vane and directly afterwards the pins 37 enter through openings 45 to lock the vane in the position shown in Fig. 4. The impeller continues to rotate to widen the space between the same and the vane and thus form the combustion chamber

23 at which time the injection and ignition of the combustible mixture takes place.

A timing mechanism, conventionally shown at 49, and operated by the endless element 50 from the shaft 18, is utilized to control the ignition of the spark plug 24.

Briefly, the cycle of operation of the engine is as follows:

With the parts in the position shown in Fig. 5, the vane 20 is locked, as illustrated in Fig. 4, and upon intake of the combustible mixture into the chamber 23, and consequent explosion, the impeller 19 is driven in the direction of the arrow. When the impeller reaches the position shown in Fig. 7, the valve 36 is opened under the control of the cam 27 to admit compressed air into the cylinder behind the rotary vane and simultaneously the cam 43 actuates the various rocker arms 39 to withdraw the locking pins 37 from engagement with the vane. The vane thereupon starts to rotate in the same direction as the impeller and a slight further movement of the latter to the position shown in Fig. 8 permits the burnt gases to escape through the exhaust opening 51 in the cylinder 15, the scavenging of the burnt gases being accelerated by the movement of the vane 20 toward said opening. Following the exhaust, the vane 20 approaches the impeller 19 and when the parts have reached the position shown in Fig. 9, the latches 46 will engage the pin 47 and thus interlock said parts. Continued movement brings the parts into the position shown in Fig. 10 at which time the pins 37 are permitted to move inwardly, first engaging the latches 46 to release the impeller and finally entering the opening 45, at which time the parts will have made a complete revolution.

What is claimed is:

1. In a rotary engine, a cylinder, a rotary impeller therein, a reaction vane also in said cylinder, and cooperating with said impeller to form a combustion chamber, releasable means for holding said vane against rotation and means operable to inject a compressed fluid in said cylinder when said vane is released to rotate said vane in the direction of rotation of said impeller to exhaust burnt gases from said cylinder.

2. In a rotary engine, a cylinder, a rotary impeller therein, a reaction vane also in said cylinder and cooperating with said impeller to form a combustion chamber, releasable means for holding said vane against rotation, means actuated by the rotation of said impeller for releasing said vane, and means operable to inject a compressed fluid in said cylinder when said vane is released to rotate said vane in the direction of rotation of said impeller to exhaust burnt gases from said cylinder.

3. In a rotary engine, a cylinder, a shaft

extending through said cylinder, an impeller fixed on said shaft, a rotary vane loose on said shaft and cooperating with said impeller to form a combustion chamber, releasable means for holding said vane against rotation and means operable to inject a compressed fluid in said cylinder when said vane is released to rotate said vane in the direction of rotation of said impeller to exhaust 10 burnt gases from said cylinder.

4. In a rotary engine, a cylinder, a shaft extending through said cylinder, an impeller fixed on said shaft, a rotary vane loose on said shaft and cooperating with said impeller 15 to form a combustion chamber, releasable means for holding said vane against rotation, means actuated by the rotation of said shaft for releasing said vane and means operable to inject a compressed fluid into said 20 cylinder when said vane is released to rotate said vane relative to the shaft and in the direction of rotation of said impeller to exhaust burnt gases from said cylinder.

5. In a rotary engine, a cylinder, a rotary 25 impeller therein, a reaction vane also in said cylinder, and cooperating with said impeller to form a combustion chamber, releasable means for holding said vane against rotation, means operable to inject a compressed fluid in said cylinder when said vane is released to rotate said vane in the direction of 30 rotation of said impeller to exhaust burnt gases from said cylinder, and means for interlocking said vane and impeller before the latter has completed a revolution.

6. In a rotary engine, a cylinder, a rotary 35 impeller therein, a reaction vane also in said cylinder, and cooperating with said impeller to form a combustion chamber, releasable 40 means for holding said vane against rotation, means operable to inject a compressed fluid in said cylinder when said vane is released to rotate said vane in the direction of rotation of said impeller to exhaust burnt gases 45 from said cylinder, means for interlocking said vane and impeller before the latter has completed a revolution, said interlocking means being released by the actuation of the holding means for said vane at the comple- 50 tion of the revolution of said vane.

7. In a rotary engine, a cylinder, a rotary impeller therein, a reaction vane also in said cylinder, and cooperating with said impeller to form a combustion chamber, means to inject compressed fluid behind said vane, after 55 the impeller has partially completed a revolution to rotate said vane to exhaust burnt gases from said cylinder, means thereupon operable to interlock said impeller and vane, and means actuated when the impeller has completed a revolution to stop the rotation of said vane and release the same from interlocking engagement with said impeller. 60

8. In a rotary engine, a cylinder, a shaft 65 extending through said cylinder, a rotary impeller fixed on said shaft, a reaction vane loose on said shaft and cooperating with the impeller to form a combustion chamber, means controlled by the rotation of said shaft to inject a compressed fluid behind said 70 vane to rotate the same after the impeller has partially completed a revolution to exhaust burnt gases from said cylinder, means thereupon operable to interlock said impeller and vane, means actuated when the impeller has completed a revolution to stop the rotation of said vane, and release the same from interlocking engagement with said impeller, and a cam on said shaft for controlling the 75 operation of the last named means. 80

9. In a rotary engine, a cylinder, a shaft 85 extending through said cylinder, a rotary impeller fixed on said shaft, a reaction vane loose on said shaft and having a recess and a communicating opening therein, means to inject compressed fluid behind said vane to rotate the same to exhaust burnt gases from said cylinder, a latch pivoted in the recess of said vane and operable to interlock said vane with said impeller before the latter has completed a revolution, a locking pin carried by the cylinder and cam controlled means actuated as said impeller approaches the completion of its revolution to initially disengage said latch from the impeller and thereafter enter the opening in said vane to stop the rotation of said vane. 90 95

In testimony whereof I have affixed my signature.
